WITNESS:

UNITED STATES PATENT OFFICE.

LESLIE A. GOULD, OF BRIDGEPORT, CONNECTICUT.

ADVERTISING DEVICE.

1,414,272.

Specification of Letters Patent. Patented Apr. 25, 1922.

Application filed August 27, 1921. Serial No. 495,895.

To all whom it may concern:

Be it known that I, LESLIE A. GOULD, a citizen of the United States, residing at Bridgeport, in the county of Fairfield and 5 State of Connecticut, have invented new and useful Improvements in Advertising Devices, of which the following is a specification.

This invention relates to an advertising 10 device, an object of the invention being to provide means for producing electric flashes which appear to be coming from the mouth of a bottle to attract attention to the advertisements carried by the bottle or located 15 adjacent thereto.

This invention also consists in certain other features of construction and in the combination and arrangement of the several parts, to be hereinafter fully described, illustrated in the accompanying drawings and 20 specifically pointed out in the appended claims.

The invention is shown in the accompanying drawing by a longitudinal sectional view, 25 parts being shown in elevation.

In this view 1 indicates a casing upon which a bottle 2, or an imitation thereof, rests. A pair of wires 3 pass through the bottle with their upper parts projecting well 30 above the mouth of the bottle and their lower ends projecting from the bottom of the bottle into the casing. These lower ends are connected by the conductors 4 with the terminals of an induction coil 5. The coil is 35 electrically connected with a transformer 6 and this transformer is provided with the connections 7 whereby it may be connected with a source of electrical supply. Both the transformer and the coil are located in the 40 casing. The wires within the bottle are insulated by passing through mica tubes 8 and the interior of the bottle is filled with colored wax or the like, as shown at 9. The parts of the wires 3 which extend above the 45 bottle are slightly divergent with their ends curving outwardly, as shown at 10.

When current is turned on the current will jump from one wire to the other to produce flashes and these flashes will occur at intervals and at successively higher points on the wires above the mouth of the bottle until

they reach the curved ends of the wires. The flashes will then start again at the mouth of the bottle so that the flashes will appear to be coming from the bottle. Advertising material can be placed on the bottle and the casing or adjacent the bottle so that the attention of passersby will be drawn to the advertised matter. The colored wax in the bottle can be made to represent liquids 60 which are being advertised.

It is thought from the foregoing description that the advantages and novel features of my invention will be readily apparent.

I desire it to be understood that I may 65 make changes in the construction and in the combination and arrangement of the several parts, provided that such changes fall within the scope of the appended claims.

What I claim is:—

1. A device of the class described comprising a receptacle, wires passing through the same and projecting above the mouth thereof, the parts of the wires within the receptacle being insulated from each other 75 and those above the receptacle being spaced apart to produce flashes by the current jumping from one line to the other and a source of electrical supply connected with the lower parts of the wires, said flashes having the 80 appearance of coming out of the receptacle.

2. A device of the class described comprising a casing, a receptacle resting thereon, a pair of wires passing through the receptacle with their upper portions projecting well 85 above the top of the same, the parts of the wires within the receptacle being insulated from each other, an induction coil within the casing connected with the lower ends of the wires, a transformer within the casing 90 connected with the coil and means for connecting the transformer with a source of electrical supply, the portions of the wires above the casing being spaced apart to produce flashes which appear to come out of 95 the receptacle.

3. A device of the class described comprising a casing, an induction coil therein, a transformer connected with the coil, means for connecting the transformer with a source 100 of electrical supply, a bottle supported upon the casing, a pair of wires passing through

the same and having their lower ends connected with the coil, said wires passing through the mouth of the bottle and projecting above the same, said projecting portions 5 being spaced apart with the space increasing upwardly and the upper ends of the wires being curved away from each other so that

flashes will be produced by the current jumping from one wire to the other, said flashes having the appearance of coming out of the 10 bottle.

In testimony whereof I affix my signature.

LESLIE A. GOULD.
